ROLLING ELEMENT ON MOVING SURFACE TOY
Henry C. Henderson, Jr., 1754 E. Sycamore,
El Segundo, Calif.
Filed Sept. 11, 1961, Ser. No. 137,191
2 Claims. (Cl. 273—109)

This invention relates generally to amusement devices and more particularly to a novel toy in which a degree of coordination and skill is required to use the toy.

A primary object of this invention, accordingly, is to provide a novel toy which not only is amusing but presents a challenge to the user insofar as his coordination is concerned.

Another object is to provide a coordination toy which is so designed that it may be disassembled into a compact structure for easy shipping and storing.

Other more general objects of this invention are to provide a novel toy appealing to persons of all ages which is essentially a self-contained unit not requiring any auxiliary apparatus, which is inexpensive to manufacture, rugged in construction, and which operates on a principle extremely simple to understand and yet constitutes an engag- gaging challenge to a person's skill.

Briefly, these and many other objects and advantages of this invention are attained by providing a closed track structure together with a free rolling element, preferably in the form of a ball, on the track structure such that the track structure may be tilted to cause the ball to roll therealong.

In the preferred embodiment of the invention, the track structure is defined by a pair of spaced parallel members having edges defining smoothly curved perimeters closing on themselves. At least one portion of the curved perimeters is concave so that when oriented in such a manner that the concave structure faces upwardly, the ball, when positioned thereon, is in stable equilibrium. With this arrangement, there is provided an initial starting point for the ball which may be easily maintained by proper holding of the toy. Rotation of the pair of spaced members about an axis normal thereto may then be executed in an attempt to cause the ball to roll about the complete circuit defined by the edges of the members themselves so that the ball may be caused to return to its starting point.

Features of the invention include a handle for facilitating manipulation of the track structure and so designed that it may be removed and stored together with the ball within the track structure itself to provide a compact unit for easy shipping and storing.

A better understanding of the invention will be had by now referring to a preferred embodiment thereof as illustrated in the accompanying drawings, in which:

FIGURE 1 is a perspective view of the assembled coordination toy of this invention;

FIGURE 2 is a cross section taken in the direction of the arrows 2—2 of FIGURE 1 in which the ball shown in FIGURE 1 has been omitted;

FIGURE 3 is a fragmentary cross section taken in the direction of the arrows 3—3 of FIGURE 1; and,

FIGURE 4 is a bottom view partly broken away to illustrate the manner in which the device may be disassembled for storage.

Referring first to FIGURE 1, the toy comprises first and second flat members 10 and 11 held in spaced parallel relationship by suitable supporting means 12. As shown, the members have edges defining smoothly curved perimeters including at least one concave curved portion 13 and at least one convex curved portion 14. Essentially, the edges of the members when disposed in like orientation as shown define a track structure following a boundary closing on itself.

2

Cooperating with the foregoing described track structure is a free rolling element preferably in the form of a ball 15. The assembly is completed by a handle 16 extending normally from the second member 11 as shown. 5 The spacing between the members 10 and 11 is less than the diameter of the ball 15 so that the ball will be properly supported on the edges of the members as illustrated. Circular openings 17 and 18 are provided in the first member 11, the purpose for which will be described sub- 10 sequently.

With the foregoing arrangement, a person may tilt or rotate the members 10 and 11 about an axis normal to the planes of the members by holding the handle 16 to cause the ball 15 to roll along the edges of the members. 15 By executing oscillating or back and forth rocking movements of the device, the person can cause the ball 15, relative to the structure, to execute a complete circle about the edges to return to its initial starting point. The concave portion 13 of the edges defining the track for the ball will hold the ball 15 in stable equilibrium when fac- 20 ing upwardly.

With particular reference to FIGURES 2 and 3, it will be noted that the support means 12 includes a plurality of rod members secured to the second member 11 and extending therefrom towards the first member 10. The member 10 in turn includes a like plurality of cup-shaped structures 19 which are bonded to the free ends of the rods 12 to hold the members in the desired spaced parallel relationship. Preferably, the members are formed from 25 plastic and by a proper extruding process, the rods 12 may be made integral with the second flat member 11 so that in the assembly of the structure, it is only necessary to bond the free ends of the rod members to the cup- shaped structures 19.

35 In addition to the foregoing, the second member 11 includes an integral central boss 20 as shown in FIGURE 3 for reception within a suitable bore 21 within one end of the handle 16. The bore 21 is made to frictionally 40 engage the boss 20 so that the handle is securely held in position when forced over the boss but yet may be re- moved.

In order to facilitate shipping and storage of the device, the openings 17 and 18 in the second member 11 are of 45 sufficient diameter to receive the ball 15. While two openings are shown, only one opening is necessary. In the event an extra ball is included with the toy, however, this additional ball would be received within the second opening.

50 Referring now to FIGURE 4, the ball 15 is shown positioned within the opening 18. Since the spacing between the members 10 and 11 is less than the diameter of the ball, a portion of the ball will extend above the second member 11. The degree of extension of the boss 20 is 55 purposely made such that when it is added to the spacing between the members 10 and 11, the total distance is greater than the diameter of the ball 15 so that the top portion of the ball 15 extending above the opening 18 is below the level of the boss 20.

60 As also illustrated in FIGURE 4, after the handle 16 has been removed from the boss 20, it may be positioned between the members 10 and 11. Thus, the entire structure may be neatly packaged within a container, the outline of which is illustrated by the dashed line 22. The 65 feature of having the end of the boss 20 extend above the level of the ball 15 will protect the ball itself during shipping and storage.

In operation, the toy may be removed from its package, 70 the handle 16 inserted over the boss 20, and the ball 15 removed from the opening 18 and placed on the tracks, preferably in the concave portion 13 as illustrated in

FIGURE 1 so that it may be easily held on the tracks when the concave portion is facing upwardly.

The user, as described heretofore, may then tilt or rotate or in any other manner rock the members about an axis generally normal to the plane of the members to cause the ball 15 to roll about the track defined by the edges of the members 10 and 11. A certain degree of skill and coordination is required to keep the ball 15 on the tracks while rotating the members thereunder. Thus, there is providing an engaging challenge to persons of all ages together with an opportunity for such person to increase his skill and coordination by attempting to maintain the ball on the track.

While only one particular embodiment of the invention has been shown and described, various modifications that fall clearly within the scope and spirit of the invention will occur to those skilled in the art. The coordination toy is therefore not to be thought of as limited to the one structure set forth merely for illustrative purposes.

What is claimed is:

1. A coordination toy comprising, in combination; first and second flat members having edges defining smoothly curved congruent perimeters including at least one concave curved portion and at least one convex curved portion; means supporting said members with like orientation in spaced parallel relationship such that said edges define tracks which close on themselves; a ball having a given diameter greater than the spacing between said members supported by said tracks for rolling movement therealong; a handle secured at one end to and extending normally from said second flat member to provide a manual holding

means for manipulating said members whereby said members may be manipulated by rotation about an axis normal to the planes of said members to cause said ball to roll along said tracks, said second member including a circular opening of diameter greater than said given diameter for receiving said ball when said toy is not in use and having a boss extending normally therefrom a given distance, said one end of said handle including an end bore receivable over said boss in frictional engagement therewith, said given distance added to the spacing between said members being greater than the diameter of said ball, whereby the portion of said ball extending above said second member when received in said circular opening is below the level of the end of said boss and whereby said handle may be removed from said boss and stored between said first and second members to provide a compact configuration for packaging of said toy.

2. A toy according to claim 1, in which said means supporting said members in spaced parallel relationship comprises a plurality of rod elements extending normally from said second member towards said first member; and a like plurality of cup structures secured to said first member and bonded to the free ends of said rod elements.
